US00D952683S

(12) **United States Design Patent** (10) **Patent No.:** **US D952,683 S**
Chen et al. (45) **Date of Patent:** **** May 24, 2022**

(54) **ELECTRONIC DEVICE WITH GRAPHICAL USER INTERFACE**

(71) Applicant: **Apple Inc.**, Cupertino, CA (US)

(72) Inventors: **Kevin Will Chen**, Cupertino, CA (US); **Teofila Connor**, San Francisco, CA (US); **Thalia Jimena Echevarria Fiol**, Cupertino, CA (US); **Aurelio Guzmán**, San Jose, CA (US); **Vincenzo Vuono**, Palermo (IT); **Christopher I. Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/816,443**

(22) Filed: **Nov. 22, 2021**

(57) **CLAIM**

The ornamental design for an electronic device with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; FIG. 4 is a fourth embodiment thereof; and, FIG. 5 is a front view of an electronic device having a display screen with the graphical user interface of FIG. 1 applied to the display screen, shown separately for completeness of illustration. The graphical user interface designs of FIGS. 2-4 may be similarly applied thereto.

The broken lines in the figures show a display screen or portion thereof, or an electronic device having a display screen, and form no part of the claimed design.
